UNITED STATES PATENT OFFICE.

HARRY VISSERING, OF KENILWORTH, ILLINOIS, ASSIGNOR TO THE OKADEE COMPANY, OF CHICAGO, ILLINOIS, A CORPORATION OF ILLINOIS.

LOCOMOTIVE-FRONT-END SUPPORT.

Application filed September 25, 1920. Serial No. 412,650.

My present invention relates in general to closure supports and more particularly to a support for the type of closure used in locomotive-boilers and commonly termed the front end plate, and has special reference to the provision of a support adapted to permit the end closure being removed and swung to one side in order to afford access to the boiler.

10 The end closure plate for the front end of a boiler shell is large and extremely heavy and is secured to the front of the boiler shell by a great number of stud-bolts and nuts circumferentially adjacent to the outer 15 edge of the front plate. To cause the front end plate to seat tightly on the front of the boiler shell, the nuts are turned up as far as practicable and when it is desired to remove the front end plate from the boiler shell to 20 afford access to the interior of the boiler, the nuts are all removed and the front end plate is moved bodily away from the boiler shell front and out of contact with the stud-bolts. The parts associated with the end 25 plate have a tendency to stick and then separation is rendered somewhat difficult. In the removal of the front end plate to a position where it is no longer supported by the stud-bolts some such means as a crane or 30 other tackle has been found necessary to carry the weight of the front end plate and this in turn has necessitated that the end plate be removed at a point where the necessary apparatus is available.

35 The principal objects of my present invention are the provision of improved means for supporting the front end plate from the engine, when detached from the boiler, and so supporting it that it may be readily re- 40 installed in operation to the boiler opening; the provision of improved means acting on the end plate whereby such end plate can be more readily moved from and to the boiler opening; the provision of a support 45 removably carried by the boiler and operatively connectible to the closure member for permitting said closure member generally to be moved away from the boiler opening and more particularly to be moved to the 50 side of the opening; the provision of a portable support for the purpose referred to adapted for rapid attachment and detachment; the provision in a boiler having a removable closure member of an improved ar-

rangement of brackets adapted to receive 55 a detachable supporting member for movably carrying the closure member; the provision of an improved supporting device adapted to permit the removal of the closure member with a minimum of strain; together with such further and additional objects as may hereinafter appear.

In attaining the objects referred to and certain additional benefits and advantages, I have provided a construction, one embodiment whereof is illustrated in the accompanying drawings, wherein—

Figure 1 is a front elevational view of a boiler having a removable front end closure plate and provided with my improved 70 detachable support shown in position to permit the removal of the end plate;

Figure 2 is a side elevational view of the structure of Figure 1, the end plate being shown as removed from the boiler front and 75 sustained by my improved support as it is swung to one side to permit access to the boiler;

Figure 3 is a plan view, partly in horizontal section, taken on the line 3—3 of 80 Figure 2 and looking in the direction indicated by the arrows; and

Figure 4 is a fragmentary lateral elevational view, partly in section, viewing a portion of the structure of Figure 1.

Referring first to Figure 1 and 2 of the drawings, it will be observed that I have here indicated a conventional form of railway locomotive boiler, 10, having an opening end normally closed by a front end closure plate, 11. The end plate, 11, is normally supported against the front end of the boiler by a circular row of stud-bolts, 12, passing through a registering series of apertures, 13, in the end plate 11. These stud-bolts, 12, 95 are screw-threaded to receive nuts, 14, by means of which the end plate, 11, may be forced against and held in close contact with the front end of the boiler, 10.

For supporting the end plate, 11, when it is removed from the boiler, 10, I have provided a supporting structure, which can be detachably secured to the boiler, and in the main removed therefrom, the removed parts being readily portable in form.

Referring now more particularly to Figures 2 and 3 of the drawings, it will be seen that I have provided on the periphery of

the boiler a suitable bracket construction which preferably includes a pair of spaced members 15, 15^a, having laterally projecting portions 16, 16^a with forward extensions 17, 17^a and bifurcated terminals 18, 18^a such terminals being apertured to receive a hinge pintle 19, 19^a.

Within the bifurcations 18, 18^a detachably rest the hinge elements 20, 20^a apertured for the passage of the pins 19, 19^a, the parts 20, 20^a being secured to the supporting pedestal 21 conveniently formed from an I-beam.

For connecting the pedestal, 21, to the front end, 11, there is secured to the upper end of the pedestal a transverse beam, 22, formed of parallel channel members, one end of which beam is secured by a tension rod, 23, to a bracket, 24, at the lower end 20 of the pedestal, 21, thus forming a truss.

For affording detachable connection between the beam, 22, and the end plate, 11, I employ a bracket, 25, fixed centrally to the upper part of the end plate, such bracket, 25, having a bifurcated portion, 26, adapted to detachably receive a suspension member, 27, which may be secured thereto by a removable hinge pintle 28^a.

The suspension member, 27, is loosely carried at the outer free end of the beam, 22, being suspended therefrom by means of the nut, 28, engaging a threaded portion of the suspension member.

In the ordinary use of a locomotive, or other structure embodying my present invention, only the bracket 15, 15^a, and 25 are carried by the boiler assembly, the end plate being supported in the customary manner by the stud-bolts, 12, and nuts 14.

When, however, it is desired to remove the end plate, 11, from support by the stud-bolts, 12, the nuts, 14, being removed, the detachable supporting structure including the principal elements 21, 22, 23 and 24, forming a portable unit, as follows: the hinge members, 20, 20^a, are brought into registry with the openings in the bifurcations 18, 18^a and the pintles, 19, 19^a are inserted in position. Then the structure is so positioned as to bring the lower end of the suspension rod, 27, into registry with the openings in the bifurcations, 26, and the pintle 28^a is inserted into position.

Referring now more particularly to Figures 1 and 4 of the drawings, it will be perceived that any desired tension may be placed upon the tension member, 23, by turning the nut, 29, upon the upper screw-threaded end of the tension rod, 23, disposed between the two webs of the composite channel beam 22, which nut bears against the chamfered face, 30, of the abutment block, 31, extending upwardly from the webs of the parallel channels.

The suspension rod, 27, is carried from

the composite channel beam, 22, by being passed loosely through an abutment block, 32, against which the nut, 28, bears.

Having, as above stated, installed the unitary detachable supporting structure and removed the nuts, 14, the end plate, 11, may be pried away from the front of the boiler, 10, in the usual manner and then swung laterally about the pintles 19, 19^a.

In view of the lateral and forward displacement of the bracket portions, 16, 16^a and 17, 17^a, the axis about which the end plate, 11, swings is positioned laterally and forwardly of the boiler and consequently the end plate slides freely over the stud-bolts, 12, on the arcs of circles of a relatively long radii to which the stud-bolts, 12, are severally tangent, thus avoiding distortion of the stud-bolts, 12, without unduly enlarging the apertures in the end plate, 11, through which said stud-bolts pass.

This separation of the end plate, 11, from the front of the boiler, 10, is facilitated by the fact that as above set forth the plate, 11, is connected for so-called universal movement relatively to the beam, 22, by virtue of the pivotal connections involved in the use of the pintle, 28^a, and the loose support by the nut, 28.

Should the end plate, 11, catch on any of the stud-bolts, 12, particularly in case the plate has gravitated downwardly, for instance by deflection of the beam, 22, compensation therefore may be made by turning up the nut 28.

Having thus described my invention and illustrated its use, what I claim as new and desire to secure by Letters Patent is—

1. In combination, a boiler having an opening, a closure member therefor, and means for supporting said closure member for movement relatively to said opening, including a supporting member and means for suspending the closure member therefrom at one end thereof, and tensioning the opposite end thereof.

2. In a device of the character described, in combination, a pivoted supporting member, a crane member secured at an angle thereto at an intermediate point of said crane member, and means for tensioning one end of said crane member.

3. In a device of the character described, in combination, a pivoted supporting pedestal member, and a crane member secured at an intermediate point at an angle thereto, and a tension member connecting one end of said crane member and said pedestal.

4. In a device of the character described, in combination, a base member, a pedestal member pivoted thereto at a plurality of spaced points, a transverse member carried by said pedestal member, and a pivoted pendant supporting member carried by said transverse member.

5. In combination, a locomotive boiler having an opening and a removable front plate therefor, a fixed support on the boiler adjacent to said front closure plate and having a portion extending forwardly thereof, a crane vertically pivotally mounted upon said support and having a laterally extending portion overlying the closure plate, and a vertically disposed suspending member on 10 the extending portion of said crane, and a horizontal pivot parallel to the face of the closure for connecting the closure plate and said suspending member.

6. In combination, a locomotive boiler having an opening and a removable front closure plate therefor, a fixed support on the boiler adjacent to said closure plate, a crane vertically pivotally mounted upon said support and having a laterally extending portion overlying the closure plate, connecting means between said closure plate and laterally extending portion, said connecting means permitting movement of the plate about a horizontal axis parallel there- 20 to but preventing substantial bodily movement of the plate laterally of said connect- 25 ing means.

7. In combination, a locomotive boiler having an opening therein, a front closure plate for said opening, a bracket on the boiler adjacent to said opening, a crane-like structure pivotally mounted upon said bracket and overlying said closure plate, a depending vertically adjustable rigid member carried by said crane-like structure, and a pivot connection between the depending member and plate forming the sole means for supporting said closure member from said crane-like structure when the closure member is removed from the boiler. 30 35 40

8. In combination, a boiler having an opening, a closure member therefor, and means for rotatably supporting said closure member for movement about angularly related axes relatively to said opening including a depending member rotatable about a vertical axis, said means also including a connection between said depending member and the closure comprising a pivot angularly related to said depending member and 45 parallel to the face of said closure plate. 50

In testimony whereof I have hereunto signed my name.

HARRY VISSERING.
